UNITED STATES PATENT OFFICE.

ROBERT F. GARDINER, OF CLARENDON, VIRGINIA.

PROCESS FOR THE PRODUCTION OF SYNTHETIC AMMONIA FROM THE AIR OR NITROGEN.

1,328,082.

Specification of Letters Patent. Patented Jan. 13, 1920.

No Drawing.

Application filed January 13, 1919. Serial No. 270,969.

(FILED UNDER THE ACT OF MARCH 3, 1883, 22 STAT. L., 625.)

To all whom it may concern:

Be it known that I, ROBERT F. GARDINER, a citizen of the United States, residing at Clarendon, in the county of Alexandria and 5 the State of Virginia, (whose post-office address is Department of Agriculture, Washington, D. C.,) have invented a new and useful Process for the Production of Synthetic Ammonia from the Air or Nitrogen.

10 This application is made under the act of March 3, 1883, chapter 143 (22 Stat. 625), and the invention herein described and claimed may be used by the Government of the United States, or any of its officers or 15 employees, in the prosecution of work for the Government, or any citizen of the United States, without payment of any royalty thereon.

Briefly stated my invention consists in the 20 synthetic production of ammonia by either passing air or nitrogen through or into an acid, or alkaline solution of any description in contact with zinc, iron, steel, or aluminum from which nascent hydrogen is being 25 evolved, either by chemical action on the aforementioned metals alone, or by the use of those metals in any physical condition between or on the electrodes in contact with any acid or alkaline solutions while a current 30 of electricity is being passed between the same.

The object of my invention is to produce synthetic ammonia from the nitrogen present in the air, or nitrogen alone, and nascent hydrogen.

35 The advantages of my invention are that synthetic ammonia can be directly produced by the passage of air or nitrogen either into or through nascent hydrogen with or without the action of electricity, in contrast to 40 the formation of ammonia by means of heat treatment in the destructive distillation of coal. The air furnishes an unlimited supply of elemental nitrogen, as compared with the necessity of separating nitrogen in the 45 combined state from combination with other elements, as is also the condition with respect to coal.

Having described my invention, I claim: 50 The process of producing synthetic ammonia consisting in bringing air into contact with an alkaline solution containing a metal from which nascent hydrogen is being evolved.

In testimony whereof, I affix my signature in the presence of two subscribing witnesses.

ROBERT F. GARDINER.

Witnesses:

EMMA WEGENER,
HELEN M. BAUER.
